UNITED STATES PATENT OFFICE.

THOMAS F. TALBOT, JR., OF CHEYENNE, WYOMING.

SAFETY-GATE FOR RAILWAY-CARS.

No. 899,494.

Specification of Letters Patent. Patented Sept. 22, 1908.

Application filed November 26, 1907, Serial No. 403,969. Renewed August 10, 1908. Serial No. 447,851.

To all whom it may concern.

Be it known that I, THOMAS F. TALBOT, Jr., a citizen of the United States, residing at Cheyenne, in the county of Laramie, State 5 of Wyoming, have invented certain new and useful Improvements in Safety - Gates for Railway - Cars; and I do hereby declare the following to be a full, clear, and exact description of the invention, such as will enable 10 others skilled in the art to which it appertains to make and use the same.

The present invention has reference to safety gates for passenger cars, and it aims, generally, to provide an exceedingly simple, 15 inexpensive, and effective device of that nature designed especially for attachment to the vestibules of the cars.

The gates ordinarily employed for that purpose are either completely detachable 20 from the arched frame of the vestibule door, or are hinged thereto, in which latter instance they are swung to one side to permit passage through the door way, while in the former instance they are disposed within the car 25 when not in actual use and must be set up and removed manually by the brakeman or other official. Where two or more vestibule cars are coupled together, the doorways in both instances above mentioned are open, to 30 afford a passage from one car to another, the gate on the rear vestibule of the rear car only being closed. It will be apparent, therefore, that in either case, there is great danger, when one car becomes suddenly uncoupled 35 from the others from any cause, to any passengers standing on the front vestibule of the uncoupled car or in the rear vestibule of the preceding car of falling or being thrown through the open door way when the train is 40 rounding a sharp curve, this being particularly true where a car becomes cut off.

It is the prime object of this invention, therefore, to avoid all liability of the occurrence of such accidents by providing a gate 45 for each vestibule of the car, which gates are held in open position when the cars are coupled together, but are automatically closed as soon as the cars are uncoupled and to remain in such position until the cars are again 50 coupled.

The invention further resides in the provision of a sliding gate which is not only adapted to move automatically into closed position as soon as the cars are uncoupled, as 55 already stated, but is also automatically opened when the cars are again coupled, the

gate on the rear vestibule of the rear car, however, being normally closed, and, therefore, unaffected by the coupling or uncoupling of this car with the preceding car. In 60 this respect, the invention more particularly resides in the provision of a gate of the type above described which is opened by means of a projecting member or members hinged thereto, such members being adapted to contact with similar members carried by the gate in the adjacent end of the car to be coupled thereto, the mutual contact of the members of both gates forcing the latter simultaneously into open position while the withdrawal of said members from such contact, when a car is uncoupled, permits the gates to simultaneously close.

The invention further resides in the formation of each gate in two sections or halves, 75 which are movable simultaneously towards and from each other, to close and open the doorway, being disposed in the latter instance in boxes or casings located on opposite sides of the door frame whose sides are slotted vertically to permit the requisite movement of the sections.

The invention will be readily understood from a consideration of the following detailed description, and its preferred embodiment is illustrated in the accompanying drawings in which similar parts or features, as the case may be, are designated by corresponding reference numerals in the several views.

Of the said drawings:—Figure 1 is a perspective view of the rear end of a vestibule passenger car, with the improved gate applied thereto, and shown in closed position. Fig. 2 is an end elevation of the car showing 95 the gate open. Fig. 3 is an enlarged vertical section through the door frame and the casings secured thereto, the gate sections being shown in open position within the casings. Fig. 4 is a transverse section taken on the line 4—4 of Fig. 2. Fig. 5 is a vertical section taken on the line 5—5 of the same figure. Fig. 6 is a vertical section taken on the line 6—6 of Fig. 1. Fig. 7 is a fragmental side elevation of the meeting ends of two cars 105 about to be coupled, showing the initial contact of the operating plates carried by the gates.

Referring to the drawings, and more particularly to Fig. 1 thereof, 10 designates, 110 generally, the vestibuled rear end of the car 11, 12 the doorway which is formed in the

end wall of the vestibule to afford a passage to the succeeding car, 13 the arched frame of said doorway, and 14 the gate. As the gates and their attendant parts at both ends of the car are identical in construction, and the manner in which they are connected with the vestibules is the same in each instance, the description of the gate shown in the figure above referred to is thought to be sufficient.

10 As shown in said figure, the gate is composed of a pair of sections 15 which are movable bodily towards and from each other through vertical slots 16 formed in the inner side walls of a pair of vertical casings 17 disposed upon opposite sides of the frame 13 and bolted at their upper and lower ends to the outer face of the end wall of the car. Each gate section comprises inner and outer posts 18 and 19 and a series of connecting cross-pieces 20 whose opposite ends are pivoted between the two members of which each post consists. The inner post 18 of each gate travels along a guide rail 21 which is disposed vertically within each casing and is secured at opposite 25 ends to the rear wall thereof, the longitudinal flange 22 with which each rail is provided extending across the outer face of the gate post last-mentioned which is thus confined therebetween and the rear wall of the casing. By 30 reason of this construction, it will be apparent when the gate sections move away from each other into their respective casings, that the inner post of each section will travel upwardly along the corresponding guide rail, 35 while the outer post will simply move across the floor of the vestibule until it reaches the side wall of the casing, at which time the inner post has reached the limit of its upward movement, each outer post being provided at 40 its lower end with a roller 23 to prevent the marring of the vestibule floor and to facilitate the movement of the sections. While the provision of the guide flanges 22 is ordinarily sufficient to hold the inner gate post 45 against lateral movement away from the guide rails, a second guide rail 24 is preferably disposed within each casing, and secured therein at opposite ends, the inner post fitting between said rails which are spaced 50 apart from each other, as shown in Figs. 3 and 4. During the movement of the sections into closed position, the inner posts travel downwardly between the guide rails, while the outer posts travel towards each 55 other, contacting when the inner posts reach their downward limits, the slots 16 having a length somewhat greater than the distance between the top and bottom cross-pieces 20 to permit the requisite pivotal movement of 60 the latter during the opening and closing of the gates.

At its upper end the inner post of each section has secured thereto a horizontal plate 25 which extends across the flanged portion 65 of the rail 21 and is hinged at its lower edge to

the inner edge of a flat link 26 whose opposite edge is similarly connected to a vertical pusher plate 27 intermediate the ends thereof, the lower end of the pusher being hinged to a strap 28 secured to the bottom wall of the 70 casing.

The gate sections are sufficiently heavy to maintain them normally closed, with their inner posts resting at their lower ends upon the floor or bottom wall of the casings, in 75 which position the pusher plates extend upwardly and outwardly from the casings, as shown in Figs. 1 and 7. Where, however, their weight is not sufficient for this purpose, a weight 29 may be secured to each horizontal plate 25 between the rail 21 and the side 80 wall of the casing.

The gates are secured to both vestibule ends of the cars, as already stated, and are so disposed thereon that the pusher plates 27 85 on the rear end of one car will exactly align with those on the front end of the succeeding car. By reason of this particular disposition, it will be apparent that when one car is moved towards another to be coupled thereto, the opposite pusher plates on the cars will contact with each other, and as the movement of the cars towards each other continues both sets of pushers will be forced 90 backwardly and upwardly into their respective casings, entering the same approximately simultaneously with the interengagement of the coupling members 30. Such movement of the pusher plates obviously 95 causes an upward movement of the corresponding inner gate posts to which they are connected by the links 26 and horizontal plates 25, effecting in consequence the opening of the gates. When, however, the cars 100 become uncoupled for any reason, the resultant separation thereof will at once permit the inner gate posts to travel downward in their respective casings, forcing the gate sections towards each other and thus closing 105 the doorways. The gate at the rear end of the rear car is normally closed, as has been 110 previously stated.

It is to be noted that both the opening and the closing of the gates is effected automatically, virtually simultaneously with the coupling and uncoupling of the cars; that the corresponding movements of the two gates likewise take effect simultaneously; and that the gate sections are held in closed position by their own weight, there being therefore 115 no necessity for the provision of latches or similar locking means.

The straps 28 to which the pusher plates are hinged may, if desired, be secured to the top wall of the casings instead of to the bottom walls thereof, as shown, in which instance the horizontal plates 25 will be fastened to the lower ends of the inner gate posts, but since such change amounts merely to a reversal of position of the parts in ques- 125 130

tion, necessity for illustration thereof is not apparent.

Other such changes and modifications may obviously be made within the scope of the 5 appended claims, as the invention is not intended to be limited to the exact details of construction shown and described.

What is claimed is:—

1. The combination, with a pair of passenger cars and their couplings, of a movable 10 gate located at the inner end of each car; and means connected with the gates for effecting their simultaneous opening when the cars are coupled.

15 2. The combination, with a pair of passenger cars and their couplings, of a movable gate located at the inner end of each car; means connected with the gates for effecting their simultaneous opening when the cars 20 are coupled; and separate means for closing the gates when the cars are uncoupled.

25 3. The combination, with a pair of passenger cars and their couplings, of a movable gate located at the inner end of each car; means connected with the gates for automatically effecting their simultaneous opening when the cars are coupled; and separate means for automatically closing the gates when the cars are uncoupled.

30 4. The combination, with a pair of passenger cars and their couplings, of a movable gate located at the inner end of each car, each gate comprising a pair of sections movable towards and from each other; devices connected with the sections of each gate for automatically moving the same away from each other when the cars are coupled; and separate devices for automatically moving the sections of each gate 40 towards each other when the cars are uncoupled.

45 5. The combination, with a pair of passenger cars and their couplings, of a movable gate located at the inner end of each car; and a pusher connected with each gate, the pusher on the gate of one car being adapted to contact with that on the other car, when the cars are coupled together, to open the gates simultaneously.

50 6. The combination, with a pair of passenger cars and their couplings, of a movable gate located at the inner end of each car; and a swinging member hingedly connected with each gate, the member on the gate of one car being adapted to contact with that on the other car, when the cars are coupled together, to open the gates simultaneously.

60 7. The combination, with a pair of passenger cars and their couplings, of a movable gate located at the inner end of each car, each gate comprising a pair of sections movable towards and from each other; and a swinging member hingedly connected to each section, the member on each section of one 65 gate being adapted to contact with that on

the opposite section of the other gate, to simultaneously move the sections of each gate away from each other when the cars are coupled together.

8. The combination, with a pair of passenger cars and their couplings, of a movable 70 gate located at the inner ends of each car, each gate comprising a pair of sections movable towards and away from each other; devices connected with the sections of each gate for holding the same in closed position when the cars are uncoupled; and a swinging member hingedly connected to each section, the member on each section of one gate 75 being adapted to contact with that on the opposite section of the other gate, to simultaneously move the sections of each gate away from each other when the cars are coupled together, to open the gates.

9. The combination, in a gate, of a pair of 80 oppositely-disposed vertical casings arranged in spaced relation to each other, each casing being provided with a longitudinal slot; a gate section connected with each casing and movable through the slot therein towards 85 and from the other section; and a pusher hinged to each casing and to the corresponding gate section for effecting the movement of the latter.

10. The combination, in a gate, of a pair 90 of oppositely-disposed vertical casings arranged in spaced relation to each other, each casing being provided with a longitudinal slot; a gate section connected with each casing and movable through the slot therein 95 towards and from the other section, each section comprising a pair of end posts and connecting cross-pieces pivoted at opposite ends thereto; a vertical guide rail disposed within each casing along which the inner post 100 of each gate section travels during the movement of the latter; and a pusher hinged to each casing and to the corresponding gate section, for effecting the movement thereof 105 towards the other gate section.

11. The combination, in a gate, of a pair 110 of oppositely-disposed vertical casings arranged in spaced relation to each other, each casing being provided with a longitudinal slot; a gate section connected with each 115 casing and movable through the slot therein towards and from the other section, each section comprising a pair of end posts and connecting cross-pieces pivoted at opposite ends thereto; a vertical guide rail disposed within each casing and provided with a longitudinal flange adapted to extend across the front face of the inner post of the corresponding gate section, said post being adapted to travel between said flange and the 120 rear wall of the casing during the movement of the gate section; and a pusher hinged to each casing and to the corresponding gate section, for effecting the movement thereof 125 towards the other gate section.

12. The combination, in a gate, of a pair of oppositely-disposed vertical casings arranged in spaced relation to each other, each casing being provided with a longitudinal slot; a 5 gate section slideable through the slot in each casing towards and from the other section and comprising a pair of end posts and connecting cross-pieces pivoted at opposite ends thereto; a vertical guide rail disposed within 10 each casing along which the inner post of the corresponding gate section travels during the movement of the latter; a plate secured to the inner post of each gate section; a weight

secured to each plate for moving the gate sections towards each other, to close the 15 gate; and a pusher hingedly connected to each casing and to the corresponding plate, for moving the gate sections away from each other, to open the gate.

In testimony whereof, I affix my signature, in presence of two witnesses.
